MAGNETIC TAPE CASSETTE

Reinhold M. Weiss, Chicago, and T. Michael Dennehey,
La Grange, Ill., assignors to Memorex Corporation

Filed Oct. 2, 1970, Ser. No. 25,306

Term of patent 14 years

Int. Cl. D14—01

U.S. Cl. D26—14

FIG. 1.

FIG. 2.

FIG. 1 is a perspective view of the novel magnetic tape cassette design of this invention;

FIG. 2 is a side elevational view thereof, the other side being substantially a mirror image thereof.

The undisclosed bottom side of the magnetic tape cassette is substantially plane and unornamented.

We claim:

The ornamental design for a magnetic tape cassette, as shown and described.
